His Attorney.

UNITED STATES PATENT OFFICE.

ALBERT W. LOHN, JR., OF LOS ANGELES, CALIFORNIA, ASSIGNOR TO ALBERT W. LOHN, JR., AND WINIFRED M. LOHN.

AUTO DOOR SIGN.

Application filed April 14, 1922. Serial No. 552,886.

To all whom it may concern:

Be it known that I, ALBERT W. LOHN, Jr., a citizen of the United States, residing in the city of Los Angeles, county of Los Angeles, and State of California, have invented certain Improvements in Auto Door Signs, of which the following is a specification.

My invention relates to auto door signs, or a sign which is complete in itself and which can be attached to the side of a car in such a way as to overlie the side or door of an automobile, or other vehicle, and have the appearance of being permanently a part thereof. It is an advantage at times to have 10 an identification mark or name on an automobile which is used in business, or in pleasure, as an advertisement, and it sometimes happens that a salesman uses his own car in the business of his company and desires to have the car so marked, and yet to 20 be able to detach the sign when desired. The object of my invention is to provide a neat and comparatively inexpensive sign of this character which can be readily detached at 25 will and which is capable of use with most cars in use. I have illustrated two embodiments of my invention on the accompanying drawings which I will now describe:

Figure 1 shows one embodiment of my invention in use, part of an automobile being indicated in light broken lines;

Figure 2 is a side elevation of another embodiment of my invention;

Figure 3 is a perspective view of the same device;

Figure 4 is a side elevation of the device shown in Fig. 1; and

Figure 5 is a sectional view thereof, on line x^6-x^6 of Fig. 4.

Referring to Figs. 1, 4 and 5, the invention comprises a sheet metal body, 1, covered

with leather, 2, or other suitable covering, and provided with two spring holding elements, 3, 3, adapted to yieldingly press against the inside of the car or door and hold the device in place. In Figs. 2 and 3, the body is bent as shown at 1^a , so as to hook over the upper edge of the door and be held in place. This style is suitable for use on a door of the thickness of the bend, but if used on a door which is not so thick, it looks awkward. In the device shown in Figs. 1, 4 and 5, the upper edge of the device may be made narrower, corresponding to the thickness of the lighter doors, while the holding fingers, or elements 3, 3, can be shaped to fit, either a thin door, or a thicker door, if the device is to be used thereon. If the upper edge of the body, which is bent to the angle, as at 1^b , Fig. 5, is narrower than the thickest door on which it is used, it will still stay in place and not look out of proportion. It will be evident that changes in details can be made without departing from the spirit of my invention and I do not limit the invention to the details except as I may be limited by the hereto appended claim.

I claim:

An auto door sign comprising a flat member having its upper edge turned at right angles to overlie upper edge of door and having a spring holding member from the horizontal part thereof extending downwardly and inwardly to yieldingly engage the inside of said door, substantially as described.

Signed at Los Angeles, California, this 7th day of April, 1922.

ALBERT W. LOHN, JR.
